UNITED STATES PATENT OFFICE.

VANDIVER J. VAN HORN, OF CHICAGO, ILLINOIS, ASSIGNOR TO UNION SPECIAL MACHINE COMPANY, OF CHICAGO, ILLINOIS, A CORPORATION OF ILLINOIS.

ORNAMENTAL-STITCH SEWING-MACHINE.

1,166,278.

Specification of Letters Patent. Patented Dec. 28, 1915.

Application filed February 13, 1911. Serial No. 608,365.

To all whom it may concern:

Be it known that I, VANDIVER J. VAN HORN, a citizen of the United States, residing at Chicago, in the county of Cook, State 5 of Illinois, have invented certain new and useful Improvements in Ornamental-Stitch Sewing-Machines, of which the following is a description, reference being had to the accompanying drawing, and to the letters 10 and figures of reference marked thereon.

The invention relates to new and useful improvements in ornamental stitch sewing machines of the type shown in my Patent No. 1,134,564, dated April 6th, 1915.

15 An object of the invention is to provide a sewing machine with thread manipulating devices whereby an ornamental stitch including a series of half twisted loops laid on the surface of the fabric is formed.

20 A further object of the invention is to provide a sewing machine, having a plurality of needles, with a thread guide for guiding an ornamental thread to be secured to one surface of the fabric, and with co-operating 25 thread engaging hooks, one of which engages the ornamental thread and forms a loop therein while the other engages a limb of the loop in said ornamental thread and carries it to the rear of the needle, whereby 30 said ornamental thread is formed into a series of loops which are secured to the surface of the material.

These and other objects will in part be 35 obvious, and will in part be hereinafter more fully described.

In the drawings which show by way of illustration one embodiment of the invention; Figure 1 is a view of the forward end 40 of a sewing machine showing the needles and the device for manipulating the ornamental thread. Fig. 2 is a sectional view through the machine, showing the mechanism for vibrating the thread engaging devices. Fig. 3 is a view taken on the line 45 3-3 of Fig. 1, looking toward the head of the machine. Fig. 4 is a perspective view of the stationary thread guide. Fig. 5 is a top plan view of one of the arms supporting one of the thread carrying devices. Fig. 6 50 is a detail view showing one position of the thread manipulating devices relative to the needles. Fig. 7 is a view similar to Fig. 6, showing another position of the thread manipulating devices. Fig. 8 is a view similar 55 to Fig. 6, showing still another position of

the thread manipulating devices. Fig. 9 is a detail view showing one form of ornamental stitch which can be made by my improved mechanism.

In the drawings, the bed plate 1, of the 60 sewing machine, carries the usual overhanging arm 2 which supports a needle lever 3 vibrating a needle bar 4 at the head of the machine in the usual manner. These parts are of the ordinary construction, and will 65 not need further description.

The needle bar 4 carries in the present embodiment of my invention two needles 5, 5. The presser foot 6, is carried by the presser 70 bar 7, and these parts are also of the usual construction.

A stationary thread guide 8 shown in perspective view in Fig. 4, is secured to the overhanging arm by means of a screw 9, which passes through an opening 10 in the 75 inner end of said thread carrier. Said thread carrier extends outward from said screw 9, and is then bent downward. At its lower end the thread carrier is bent laterally as at 11 and provided with a thread 80 guiding eye 12. This thread guide is for the ornamental thread which is to be secured to the fabric and said thread after passing through the thread guide, may if desired, be passed underneath a tension spring 13 carried by the thread guiding arm 8 and through an opening 14 in said thread guiding arm and from thence to a thread guide 15 carried by the upper end of the needle bar. Said thread is then passed underneath 85 a stationary thread guiding wire 16, mounted on the head of the machine, and is then led to the rear of the machine, and through a tension device if desired, in the usual manner. The needles 5, 5, are threaded in the 90 usual manner and any suitable complementary stitch forming mechanism co-operates therewith, whereby a plurality of parallel lines of stitching on the upper face of the 95 fabric may be produced.

The first implement to engage the ornamental thread passing through the guide eye 12, is a thread carrying hook 17, which is carried by a curved arm 18, shown in detail in Fig. 5. Said curved arm 18 extends to 105 the rear of the machine where it is mounted on a supporting stud 19 (see Fig. 3). Said supporting stud 19, carries a projecting arm 20 to which is connected a link 21. The other end of the link 21 is pivotally connect- 110

ed to an arm which is rigidly connected to a shaft 22, mounted in suitable bearings in the rear side of the machine.

The shaft 22 as shown in Fig. 2 carries a 5 slotted arm 23 to which a link 24 is connected by means of a stud and nut 25. The link 24 is at its other end connected to an eccentric 26 carried by a gear wheel 27, which in turn coöperates with a gear wheel 10 28 mounted on the main shaft 29. The size of the gear wheels 27 and 28 are such that the arm 18 is moved from one side of the line of feed to another, for each up and down movement of the needle bar. In other 15 words, the needle bar reciprocates twice to one reciprocation of the arm 18. The thread carrying hook 17 is secured in a depending shank 30 carried by the arm 18 by means of a set screw 31. Said hook 17 at its lower 20 end is bent laterally and at its outer end is bent away from the thread guiding eye 12 as the parts are positioned in Fig. 1, so as to provide a hook which will engage the ornamental thread when said thread carrying 25 hook moves underneath the thread guiding arm 8.

The parts above described are so positioned and timed that the thread guiding hook 17 moves from a position slightly at 30 the right of the thread guiding eye 12, to a position at some distance beyond the left hand needle as viewed in Fig. 1. This movement of the thread hook 17 will form a loop in the ornamental thread, one limb *a* of 35 the loop (see Fig. 7) extending from the hook to the thread guiding eye 12 and the other limb *b* of the loop extending to the material where it has been secured by the previous needle stitches.

40 Coöoperating with the thread hook 17 and the thread guiding arm 8, is a second thread hook 32. This thread hook is mounted on a shaft 33 carried by a bracket 34 mounted on the head of the machine. The shaft 33 carries a projecting arm 35 to which is connected a link 36 (see Fig. 3). The other end of the link 36 is connected to a depending arm 37 which in turn is mounted on a sleeve 38 carried by the shaft 22.

45 The sleeve 38 carries an arm 39 which in turn is pivotally connected with a link 40 coöperating with an eccentric 41 on the main shaft 29. The thread guiding hook 32 is clamped to the lower end of the shaft 33 by a set screw 42. Said arm extends outward from the shaft 33, and is then bent downward; thence laterally as at 42. The free end of the portion 42 is bent downward to form a hook 43, which engages the ornamental 50 thread. Said thread hook 32 is so positioned and timed that the hook 43 carried thereby is moved from a position in front of the thread extending from the hook 17 to the thread eye 12, when the hook 17 is at the 55 left of the needles, as viewed in Fig. 7, to a

position in rear thereof as shown in Figs. 6 and 8. Said hook 43 is also positioned so that it moves over the loop of thread formed in the ornamental thread by the hook 17. Inasmuch as the limb *b* of the loop extends 70 from the hook 17 downward to the fabric, said limb would be out of the path of the hook 43 while the other limb *a* will lie in the path of the hook 43. When therefore, the hook 17 is in the position shown in Fig. 7, 75 the hook 43 will engage the portion *a* of the ornamental thread and carry the same entirely in rear of two needles. These movements result in forming a half twisted loop 80 of thread. The needles as clearly shown in Figs. 6 to 8 inclusive are arranged slightly diagonal of the line of feed so that successive needle punctures *c'*, *c'*, and *c''*, *c''*, as shown in Fig. 9 will be formed. When the needles are raised out of the needle punctures 85 *c*, *c*, and are about to form the needle punctures *c'*, *c'*, the hook 17 carries the ornamental thread to the position shown in Fig. 7, and then the hook 43 engages the limb *a* of the loop and carries it to the rear of the 90 path of the needles so that the punctures *c'*, *c'* will be formed at the left of the portion *a* of the thread, and the thread running from the needle punctures *c* to *c'* will bind the ornamental thread to the upper 95 face of the fabric.

The stroke of the hook 17 is sufficient so as to draw off sufficient thread to form what may be termed an extended loop and therefore, the needle puncture *c''* of the left hand 100 needle in Fig. 1 will enter again into the loop formed in the ornamental thread, while both the needle punctures *c'* and *c''* of the right hand needle, will be between successive loops. When it is desired to increase the 105 throw of the hook 17 in order to further extend the loop in the ornamental thread, the connection between the link 24 and the slotted arm 23 may be shifted.

As clearly shown in Fig. 6, the presser 110 foot is provided with a rearwardly projecting portion 44, which extends between the needles and which will aid in positioning the loop in the ornamental thread, after it has been dropped by the hook 17, so that the second downward movement of the left hand needle will enter said extended loop.

While I have herein shown and described the movements of the hooks as capable of forming a particular stitch, it is evident 120 from certain aspects of the invention, the hooks may be given a slightly different timing or a slightly different movement relative to each other.

Having thus particularly described my 125 invention, what I claim as new and desire to secure by Letters Patent, is:—

1. A sewing machine comprising in combination, stitch-forming mechanism including a plurality of needles, a thread guide 130

for guiding an ornamental thread, a thread-carrying hook engaging said ornamental thread between the thread guide and the material and forming a loop in said ornamental thread, and a second thread-guiding hook movable independently of said thread guide for simultaneously engaging one limb of said loop and carrying the same to a position in rear of the path of the needles.

2. A sewing machine comprising in combination, stitch forming mechanism, including a plurality of needles, a stationary thread guide located at one side of said needles, a thread carrying hook engaging the thread carried by said thread guide and moving in front of the needles to a position at the opposite side thereof from the thread guide and a second thread hook coöperating with said first named hook and thread guide and moving from a position in front of said needles to a position in rear thereof.

3. The combination with a plurality of needles, a thread guide for guiding an ornamental thread, a thread carrying device coöperating with said thread guide, means for giving said thread carrying device and said thread guide a relative movement whereby a loop of thread is formed extending from one side of the needles to the other side thereof, and a thread engaging device movable independently of the first named thread guide and moving at an angle to the path of movement of said thread-carrying device for engaging, and carrying one limb of said loop to the rear of the path of said needles.

4. The combination with a plurality of needles, a thread guide for guiding an ornamental thread, a thread hook for engaging the ornamental thread between the thread guide and the material, means for moving said hook whereby an extended loop is formed in said ornamental thread and a thread engaging device moving at an angle to the path of movement of said hook for engaging and carrying one limb of the loop to the rear of the path of the needles, whereby said extended loop is positioned so that one of said needles will enter twice into said loop.

5. The combination with stitch forming mechanism, a stationary thread guide for guiding an ornamental thread, a thread hook, means for supporting said hook whereby the same moves in a path below said thread guide, and in front of said

needles, a second thread carrying hook and means for supporting said second thread carrying hook, whereby it moves in a path intersecting the plane of the needles and across a line passing through said first named hook and said thread guide.

6. The combination with a plurality of needles, of a stationary thread guide located at one side of said needles for guiding an ornamental thread, a thread engaging hook for engaging the ornamental thread between said thread guide and the material, means for moving said thread engaging hook from one side of said needles to the other in a path in front of said needles, a second thread engaging hook moving in a path between said needles, and from a position in front of the first named thread carrying hook to a position in rear of said needles.

7. The combination with a plurality of needles, of a thread guide for guiding an ornamental thread, a thread carrying hook for engaging the ornamental thread between the thread guide and the material, means for moving said thread hook from a position at one side of said needles, to a position at the other side of said needles, a thread engaging device for engaging the thread between said hook and said thread guide, and carrying the same to a position in rear of the needles, and means whereby the stroke of the first named thread hook may be varied.

8. The combination with a plurality of needles, a presser foot, a rearwardly projecting portion carried by the presser foot and extending between the needles, a stationary thread guide located at one side of said needles for guiding an ornamental thread, a thread hook for engaging the thread between said thread guide and the material, and moving to the other side of the needles, means for moving said hook whereby an extended loop is formed in the ornamental thread, a thread engaging device for carrying one limb of said loop to the rear of the path of said needles, said projection on the presser foot operating to position said extended loop after released by the hook, whereby one of said needles will enter a second time into said loop.

In testimony whereof I affix my signature, in presence of two witnesses.

VANDIVER J. VAN HORN.
